ETHYLBENZENE FROM C₈ AROMATIC HYDROCARBONS

David A. McCaulay, Chicago, Ill., and Arthur P. Lien, Highland, Ind., assignors to Standard Oil Company, Chicago, Ill., a corporation of Indiana

Application March 21, 1955, Serial No. 495,438

4 Claims. (Cl. 260—668)

This invention relates to the separation of mixed C₈ aromatic hydrocarbons into a xylene fraction that is substantially free of ethylbenzene and an ethylbenzene or diethylbenzene fraction. More particularly, it relates to a combination process for the separation of o-xylene free mixed C₈ aromatic hydrocarbons into a substantially ethylbenzene-free m- and p-xylene fraction and a substantially pure ethylbenzene fraction with no loss to production of ethylxylene.

As the source material for the production of styrene, ethylbenzene is a very important commercial material. Owing to a simultaneous large demand for benzene, which is the primary source of commercial ethylbenzene, ethylbenzene is in short supply and is forced to continue in short supply. Ethylbenzene occurs in nature in most petroleum oils. Also, it occurs in the light oil derived as a by-product of the carbonization of coal. In recent years, a tremendous quantity of ethylbenzene has been made available, potentially, in the product from petroleum naphtha conversion process, particularly the well known "hydroforming" process and "platforming" process. However, the ethylbenzene from all these sources is associated with dimethylbenzenes, i. e., xylenes. This mixture of C₈ aromatic hydrocarbons can be resolved by superfractional distillation into an ortho-xylene concentrate and a mixture of ethylbenzene, para-xylene, and meta-xylene. This mixture is not a desirable feed to a styrene production process. The best known method for resolving the mixture of C₈ aromatic hydrocarbons into high purity fractions, i. e., fractions containing 95% or more of the desired compound, is by the fractional crystallization technique. This method is quite involved and quite expensive when high purity products are desired.

Other methods involve the separation of ethylbenzene by chemical reaction techniques. It is known that substantially pure ethylbenzene is rapidly and substantially completely disproportionated to diethylbenzene and benzene by the action of a liquid HF-BF₃ treating agent. It is also known that the treatment of a mixture of C₈ aromatic hydrocarbons and non-aromatic hydrocarbons with liquid HF-BF₃ treating agent results in a product containing diethylbenzene, ethylxylene, some ethylbenzene and xylenes. The C₁₀ aromatic fraction consisting of diethylbenzene and ethylxylene is very close boiling and cannot be resolved by superfractional distillation; furthermore, the production of ethylxylene results in a decreased yield of xylene. Also, the treatment of the so-called "close-boiling" xylene cut of a hydroformate or platformate results in a large loss of ethylbenzene to the non-aromatic product of liquid HF-BF₃ treatment. The greater the amount of non-aromatic hydrocarbons in the feed to the liquid HF-BF₃ treatment, the larger the loss of ethylbenzene. (This ethylbenzene can be recovered from admixture with the non-aromatic hydrocarbons by an extractive distillation process such as the aromatic separation process using phenol as the separating agent.)

2

It is an object of this invention to treat a mixture of at least one xylene isomer other than o-xylene and ethylbenzene to produce a xylene fraction that is substantially free of ethylbenzene without loss of xylene. Another object is the treatment of an essentially o-xylene-free mixed C₈ aromatic hydrocarbon feed to produce a xylene fraction substantially free of ethylbenzene and a diethylbenzene fraction that is free of ethylxylene. Still another object is a process for the treatment of essentially o-xylene-free mixed C₈ aromatic hydrocarbons to produce a maximum yield of essentially pure diethylbenzene and a maximum yield of a xylene fraction that is substantially free of ethylbenzene. Yet another object of the invention is to convert diethylbenzene into ethylbenzene. A particular object of the invention is the treatment of a close-boiling feed consisting essentially of a mixture of m-xylene, p-xylene and ethylbenzene to produce a product that is substantially free of ethylbenzene and a substantially pure ethylbenzene product.

Another particular object is the treatment of a close-boiling feed comprising essentially a mixture of C₈ aromatic hydrocarbons which has been fractionated to remove essentially all the o-xylene to produce a xylene product substantially free of ethylbenzene and a substantially pure meta-diethylbenzene product.

It has been found that a mixture of ethylbenzene and at least one xylene isomer other than o-xylene can be treated with liquid HF and BF₃ to produce a xylene fraction substantially free of ethylbenzene and a diethylbenzene fraction that contains no detectable amount of ethylxylene. This ethylbenzene conversion process involves careful control of operating conditions, particularly the relationship of contacting temperature and contacting time. (Under the conditions of this process, o-xylene interacts with ethylbenzene to form 1,2-dimethyl-4-ethylbenzene.)

Secondly, it has been found that maximum conversion of ethylbenzene to diethylbenzene can be attained only by the treatment of said ethylbenzene-xylene feed in the absence of benzene and/or toluene; and also by carrying out the ethylbenzene conversion reaction in a single substantially homogeneous liquid phase system. This single substantially homogeneous liquid phase can be attained only by the use of a feed which contains not more than about 2-3 volume percent of non-aromatic hydrocarbons, preferably less than about 1% of non-aromatic hydrocarbons.

It has been found that in addition to the effect of contacting temperature and/or contacting time, the amount of BF₃ present in the contacting zone determines the degree of conversion of ethylbenzene to diethylbenzene and/or ethylxylene. In order to produce a diethylbenzene aromatic hydrocarbon product by the treatment of a mixture of ethylbenzene and meta and/or para-xylene, it is necessary to use at least 1 mole of BF₃ per mole of xylene present in the contacting zone. That is, all the xylene must be held in the form of an HF-BF₃-xylene complex. By complexing all the xylene, the possible reactions are reduced to the disproportionation of ethylbenzene to diethylbenzene. In the presence of uncomplexed xylene, the predominating reaction is the interaction of ethylbenzene and xylene to form ethylxylene. In order to disproportionate ethylbenzene into diethylbenzene, additional BF₃ must be present in the contacting zone over the at least 1 mole per mole of xylene present therein. Although appreciable conversion to diethylbenzene is obtained with only trace amounts of additional BF₃ present, the conversion of ethylbenzene is maximized by the use of at least 0.5 mole of additional BF₃ per mole of ethylbenzene present in the feed to the ethylbenzene conversion process.

Better control of the product distribution is attained by the use of more than the minimum amounts of BF_3 . In general, about 1 mole of BF_3 per mole of C_8 aromatic hydrocarbon in the feed is used. However, more than this amount may be used, e. g., 5 moles. It is preferred to operate with between about 1.5 and 3 moles of BF_3 per mole of C_8 aromatic hydrocarbon present in the feed to the ethylbenzene conversion process.

The process of this invention must be carried out under substantially anhydrous conditions. The liquid HF used in the process should be substantially anhydrous, i. e., the liquid HF should contain less than 2 or 3% of water.

The liquid HF not only participates in the formation of the polyalkylbenzene- BF_3 -HF complex, but it also acts as a solvent for said complex. Therefore, it is necessary to use at least enough liquid HF to participate in the formation of the complexes and also to dissolve the complexes. In general, at least about 2 moles of liquid HF per mole of C_8 aromatic hydrocarbon in the feed should be used. More than this minimum amount may be used, e. g., as much as 50 moles. It is preferred to use in the ethylbenzene conversion process between about 6 and 15 moles of liquid HF per mole of C_8 aromatic hydrocarbon in the feed.

A liquid HF solution of meta and/or para-xylene- BF_3 -HF complex and diethylbenzene- BF_3 -HF complex, at ambient temperatures, slowly changes to a liquid HF solution of xylene- BF_3 -HF complex, diethylbenzene- BF_3 -HF complex and ethylxylene- BF_3 -HF complex. If the liquid HF solution is permitted to stand for a sufficient time, the solution will contain only meta-xylene- BF_3 -HF complex and 1,3,5-ethylxylene- BF_3 -HF complex.

At temperatures below about 125° F. it is possible to treat a feed mixture of meta-xylene, para-xylene and ethylbenzene under the above described conditions of liquid HF and BF_3 usage, to produce a liquid HF solution containing only a xylene complex, a diethylbenzene complex and some dissolved ethylbenzene and benzene. Apparently under the conditions of liquid HF- BF_3 usage described above, the only reaction in the liquid HF phase is the disproportionation of ethylbenzene to diethylbenzene, chiefly meta-diethylbenzene and, under some conditions of temperature and time, only the meta-diethylbenzene. It is believed that the diethylbenzene reacts with the xylene to produce ethylxylene and ethylbenzene, which ethylbenzene disproportionates to form more diethylbenzenes; and this process continues until an equilibrium condition is arrived at; by a proper adjustment of temperature and time, it is possible to convert the diethylbenzene virtually completely to ethylxylene so that a substantially pure ethylxylene product is attained. However, at temperatures below about 125° F. a finite period of time passes before detectable amounts of ethylxylene are produced. Thus by taking advantage of this "induction period" it is possible to treat a mixture of meta and/or para-xylene and ethylbenzene with liquid HF and BF_3 to produce a xylene fraction that is substantially free of ethylbenzene and a diethylbenzene fraction that is free of detectable amounts of ethylxylene.

At temperatures above 125° F., the induction period is so short that appreciable amounts of ethylxylene are formed even though the liquid HF solution of aromatic hydrocarbon complexes is quenched. At a temperature of 125° F. the maximum contacting time for the production of essentially pure diethylbenzene is on the order of 2 or 3 minutes. Slightly higher temperatures may be tolerated by reducing the contacting time and by quenching the liquid HF solution of complexes, e. g., by the addition of liquid propane. It is only necessary to reduce the temperature of the liquid HF complex solution to below 100° F. in order to increase the induction period to a workable time. At a contacting temperature of about 100° F., the maximum con-

tacting time is about 10 minutes; at about 70° F., the maximum contacting time is about 30 minutes.

The temperature of contacting may be as low as 0° F. because the ethylbenzene conversion to diethylbenzene reaction reaches equilibrium within a few minutes even at this low temperature. The "induction period" at this low temperature is several days. When it is desired to produce meta-diethylbenzene as the product and particularly when meta-xylene is also a desired product, it is preferred to carry out the ethylbenzene conversion process at a temperature between about 70° and 100° F. and to operate for times approaching the maximum, i. e., between about 10 minutes and 30 minutes wherein the longer times correspond to the lower temperatures.

Even at higher temperatures and longer contacting times some ethylbenzene will remain unconverted. At the preferred conditions of liquid HF and BF_3 usage and the preferred temperature-time relationship, between about 90 and 95% of the ethylbenzene in a feed consisting essentially of ethylbenzene and m- and/or p-xylene will be converted to meta-diethylbenzene. The unconverted ethylbenzene will be recovered along with the xylene. However, in all cases the amount of ethylbenzene present in said xylene fraction will be low enough that the xylene fraction is substantially ethylbenzene-free, i. e., the xylene fraction will contain about 5% or less of ethylbenzene. The higher the temperature of operation and the closer the approach to the maximum contacting time, the lower the content of ethylbenzene in the product xylene fraction.

Substantially-liquid HF-insoluble hydrocarbons such as paraffins and naphthenes readily wash ethylbenzene out of the acid phase. A "close-boiling" mixture of C_8 aromatic hydrocarbons and non-aromatic hydrocarbons such as is obtained by distillation of a hydroformate will normally contain about 50 volume percent of non-aromatic hydrocarbons such as paraffins, naphthenes and olefins in addition to small amounts of organic sulfur compounds. By superfractionation, it is possible to obtain a C_8 aromatic hydrocarbon concentrate which contains on the order of 90% of aromatic hydrocarbons consisting of ethylbenzene, xylene isomers and minor amounts of C_8 aromatic hydrocarbons. When a C_8 aromatic hydrocarbon feed such as is described in this paragraph is contacted with a sufficient amount of liquid HF and at least about 1 mole of BF_3 per mole of aromatic hydrocarbon in the feed, a raffinate phase and an extract phase are formed. The raffinate phase contains essentially all the non-aromatic hydrocarbons. It has been found that regardless of the amount of contacting carried out between the raffinate phase and the extract phase, considerable amounts of ethylbenzene are present in the raffinate phase.

When treating a feed containing as little as 10 volume percent of non-aromatic hydrocarbons, between about 20 and 30% of the ethylbenzene present in the feed will be found in the raffinate phase and will be lost to the diethylbenzene product. Apparently the presence of non-aromatic hydrocarbons as a separate raffinate phase very adversely affects the ability of the liquid HF- BF_3 treating agent to convert and maintain ethylbenzene in the extract phase in the form of diethylbenzene. (Ethylbenzene recovery by extractive distillation processes or other extractive processes from the raffinate phase is not considered as "recoverable ethylbenzene" within the meaning of this invention.)

The presence of benzene and toluene markedly reduces the degree of conversion to diethylbenzene.

The presence of dissolved non-aromatic hydrocarbons and dissolved and/or complexed organic sulfur compounds in the acid phase does not appear to adversely affect the disproportionation reaction of ethylbenzene to diethylbenzene. The solubility of non-aromatic hydrocarbons in liquid HF is increased somewhat by the pres-

ence of an aromatic complex in the liquid HF. However, under the conditions of liquid HF and BF_3 usage described above, not more than on the order of 2-3 volume percent of non-aromatic hydrocarbons can be tolerated in the feed if operation without a raffinate phase in the contacting zone is desired. The maximum content of non-aromatic hydrocarbon will be dependent on the amount of liquid HF used and somewhat on the amount of BF_3 used. It is preferred to operate with a minimum of non-aromatic hydrocarbon in order to improve the purity of the xylene product fraction. The preferred feed stock to the ethylbenzene conversion process comprises essentially a mixture of at least one xylene isomer other than o-xylene and ethylbenzene, i. e., the feed stock contains less than about 2 volume percent of non-aromatic hydrocarbons and the naturally occurring amounts of organic sulfur compounds, in addition to meta and/or para-xylene and ethylbenzene.

The feed stocks obtained from hydroformates or platformates contain some small amounts of olefins. These olefins readily alkylate some of the aromatic hydrocarbons and form alkyl aromatics which have a boiling point higher than the diethylbenzene product and may be readily separated therefrom by distillation. The organic sulfur compounds present in feeds from hydroformates and platformates are readily removed from the product hydrocarbons by treatment with sulfuric acid or by treatment with substantially anhydrous liquid HF in the absence of BF_3 .

The non-aromatic hydrocarbons, other than olefins, present in a mixed feed boil in about the same range as the xylene isomers. As a consequence these non-aromatic hydrocarbons are concentrated in the product xylene fraction. Even when operating with a maximum of about 2-3 volume percent of non-aromatics in the feed, the product xylene fraction will contain 5% or less of non-aromatic hydrocarbons. This is usable in most operations requiring high purity xylene. The non-aromatic content cannot be decreased by washing of the complex containing liquid HF solution with a diluent such as butane, pentane, or hexane, owing to the fact that the diluent promotes undesired side reactions. These side reactions involve the disproportionation of diethylbenzene to tri- and higher ethyl content polyethylbenzenes. In addition to this, the presence of diluent hydrocarbons in a washing operation appears to promote the isomerization of meta-diethylbenzene to the ortho- and para-diethylbenzene isomers.

Although it is preferred to operate the ethylbenzene conversion process using a feed stock and amounts of liquid HF and BF_3 such that substantially only one liquid phase is present in the contacting zone, it is to be understood that some gaseous BF_3 will be present under all operating conditions. In the contacting zone, the term "single substantially homogeneous liquid phase" is to be understood as including (a) conditions such that only a liquid HF solution is present, or (b) such that a barely detectable amount of raffinate phase is present along with the liquid HF solution.

Diethylbenzene and triethylbenzene can be reacted with benzene in the presence of liquid HF and BF_3 treating agent to produce a mixture consisting essentially of diethylbenzene, triethylbenzene, benzene and ethylbenzene. The ethylbenzene may be recovered as essentially pure ethylbenzene by distillation from the product mixture. Hereinafter the reaction of diethyl- and triethylbenzene with benzene to form ethylbenzene is spoken of as "the diethylbenzene conversion process."

The feed stock to the diethylbenzene process should be essentially pure diethylbenzene and/or triethylbenzene or mixtures of these with other polyethylbenzenes. In order to maximize the yield of ethylbenzene, it is necessary that other aromatic hydrocarbons such as xylene and toluene be absent from the contacting zone.

The amount of benzene present in the feed mixture of

5 diethylbenzene (hereinafter it is to be understood that "diethylbenzene" may include triethylbenzene, etc.) must be at least 1 mole for each ethyl group that is transferable; a transferable ethyl group is one that will result in the reduction of the number of ethyl groups on the polyethylbenzene and result in the formation of a molecule of ethylbenzene, e. g., triethylbenzene contains two transferable ethyl groups; thus theoretically 1 mole of triethylbenzene could react with 2 moles of benzene to form 3 moles of ethylbenzene. In the case of diethylbenzene itself, at least 1 mole of benzene must be present per mole of diethylbenzene present. However, the yield of ethylbenzene is improved by the use of more than the theoretical amount of benzene; as much as 20 moles per mole of transferable ethyl groups may be used. The preferred usage of benzene is between about 4 and 7 moles per mole of transferable ethyl group; or, in the case of a diethylbenzene feed, between about 4 and 7 moles per mole of diethylbenzene.

20 Substantially no reaction takes place between diethylbenzene and benzene when more than 1 mole of BF_3 is present per mole of diethylbenzene. Apparently the reaction does not proceed at an appreciable rate unless some uncomplexed diethylbenzene is present in the complex-containing HF solution. While some reaction will occur at very low BF_3 usages such as 0.1 mole per mole of diethylbenzene, the degree of conversion is low and the reaction rate is very slow. It is preferred to operate the diethylbenzene conversion process with between about 0.3 and 0.5 mole of BF_3 per mole of diethylbenzene.

25 Just as in the ethylbenzene conversion process, sufficient liquid HF must be present to participate in the formation of the diethylbenzene complex and also to dissolve said complex. Thus the amount of liquid HF used should be from at least about 2 moles to as much or more than 50 moles per mole of diethylbenzene in the feed to the contacting zone. However, it is preferred to operate with a liquid HF usage between about 10 and 25 moles per mole of diethylbenzene in the contacting zone.

30 Somewhat elevated temperatures of contacting are desirable in order to speed up the reaction rate. The maximum temperature of contacting should be below about 200° F.; side reactions involving hydrogen transfer occur at temperatures in excess of about 200° F. It is preferred to operate at between about 100° and 150° F. Lower temperatures may be used if either degree of conversion is sacrificed or extremely long contacting times are tolerable.

35 By operating for a sufficient time at a particular contacting temperature, it is possible to attain a constant product distribution condition; the amount of ethylbenzene produced is dependent not only on temperature and contacting time, but also on the amount of benzene present in the contacting zone. Examples of suitable contacting times at particular temperatures are: 60° F., about 16 hours; 100° F., about 2 hours; 150° F., 15-30 minutes.

40 The annexed drawing which is a part of this specification shows an illustrative embodiment of a combination process for the treatment of a feed comprising essentially ethylbenzene, para- and meta-xylene to produce a substantially pure ethylbenzene product and a xylene fraction that is substantially free of ethylbenzene. It is to be understood that many features of process equipment, such as pumps and valves, have been omitted from this schematic flow drawing, as these details may be readily added thereto by one skilled in the art.

45 In this illustration, the feed consists of: 2 volume percent of non-aromatic hydrocarbons; this includes a very slight amount of organic sulfur compounds and olefinic hydrocarbons. The total sulfur content of the feed is about 0.01 weight percent. The remainder of the feed consists of C_8 aromatic hydrocarbons in the following 50 molar percentages on aromatic hydrocarbon: ethylben-

zene, 15; ortho-xylene, trace; meta-xylene, 61 and para-xylene, 24. This feed was obtained by extractively distilling, with phenol as the separating agent, a hydroformate cut boiling between about 270° and 300° F., which cut had contained about 12% of non-aromatic hydrocarbons, and then distilling in a superfractionator the C₈ cut to eliminate all the o-xylene and C₉ aromatics; some m- and p-xylene was lost in this distillation.

The feed is passed from source 11 by way of line 12 into mixer 13. Substantially anhydrous liquid HF from source 14 is passed by way of valved line 16 and line 17 into mixer 13. In this illustration, 9 moles of liquid HF per mole of aromatic hydrocarbon in the feed are present in mixer 13. BF₃ from source 18 is passed through valved line 19 and line 21 into mixer 13. In this illustration, 1.5 moles of BF₃ per mole of aromatic hydrocarbon in the feed are present in mixer 13.

Mixer 13 is provided with heat exchanger 23. The complex formation is exothermic and heat exchanger 23 may be used either to withdraw heat of complexing or to raise the temperature of the materials to the desired reaction temperature. Mixer 13 may be any form of mixing chamber or may be provided with a motor-driven agitator. In mixer 13, the feed is dissolved into the liquid HF partly in the form of a complex, and partly in free solution to form a single homogeneous liquid phase.

The liquid phase and undissolved gaseous BF₃ are passed from mixer 13 by way of line 24 into reactor 26. Reactor 26 is provided with heat exchangers 27 and 28, which heat exchangers maintain the desired contacting temperature in reactor 26. In this illustration, the contacting temperature is 90° F. and the contacting time is about 10 minutes. No agitation is needed in reactor 26 as the single homogeneous liquid phase provides more than adequate intimacy of contacting.

At the completion of the reaction time, the liquid HF solution is withdrawn from reactor 26 by way of line 29 and is passed into decomposer 31. Decomposer 31 is a vertical vessel provided with an internal heat exchanger 32 and with a few fractionating trays not shown. In decomposer 31, the HF and the BF₃ are removed from the single homogeneous liquid phase and pass out of decomposer 31 by way of line 33. Decomposer 31 should be operated in such a way that the BF₃ and HF are removed at such a rate that substantially no further reaction takes place. Decomposer 31 may be operated at temperatures below the boiling point of liquid HF by the use of a vacuum or may be operated at elevated temperatures, e. g., 150° F. In this illustration, decomposer 31 is operated at about 70° F. under a slight vacuum provided by vacuum pump 34.

HF and BF₃ are passed overhead through line 33, vacuum pump 34 and line 36 into heat exchanger 37. In heat exchanger 37, the HF vapors are condensed. The liquid HF containing some dissolved BF₃ and the gaseous BF₃ is passed by way of line 38 into gas separator 39. A liquid HF stream saturated with BF₃ is withdrawn from separator 39 and recycled to mixer 13 by way of line 17.

Gaseous BF₃ is withdrawn from separator 39 and is recycled to mixer 13 by way of line 21. Gradually a build-up in the BF₃ of hydrogen sulfide will occur from decomposition of organic sulfur compounds in decomposer 31. Periodically, BF₃ from separator 39 should be withdrawn and passed through a purification zone, not shown, to remove undesired gases such as H₂S.

Preferably only a portion of the BF₃ and the HF are removed in decomposer 31. The remaining BF₃ and HF are removed from the decomposer along with the hydrocarbons.

From the bottom of decomposer 31 hydrocarbons and remaining HF and BF₃ are withdrawn and passed by way of line 41 into fractionator 42. Fractionator 42 is provided with an internal heat exchanger 43. In fractionator 42, benzene formed in the ethylbenzene conversion is passed overhead along with HF and BF₃ through valved

line 44. A bottoms stream is withdrawn from fractionator 42 and is passed by way of line 46 into fractionator 47, which is provided with internal heat exchanger 48.

There is taken overhead from fractionator 47 by way of line 49 a product xylene fraction which consists of meta and para-xylenes, wherein the m-isomer is present in an amount greater than in the feed, the non-aromatic hydrocarbons present in the feed, about 3 mole percent of ethylbenzene and a small amount of organic sulfur compounds. From the bottom of fractionator 47 a substantially pure diethylbenzene fraction is withdrawn by way of line 51. This diethylbenzene fraction, from operation on this type of feed, contains higher boiling alkylbenzenes, trace amounts of ethylxylenes and some organic sulfur compounds.

The product diethylbenzene from fractionator 47 may be treated to remove sulfur compounds and increased in purity by distilling away the higher boiling alkylbenzene.

However, in this illustrative embodiment, the product diethylbenzene is passed by way of lines 51 and 52 into mixer 53. The benzene and HF-BF₃ fraction from fractionator 42 is passed by way of valved line 44 and lines 54 and 56 into mixer 53. Make-up benzene from source 57 is passed by way of lines 58 and 56 into mixer 53. In this illustration, 6 moles of benzene are present in mixer 53 for each mole of transferable ethyl group present in mixer 53.

Substantially anhydrous liquid HF from source 14 is passed by way of valved line 59 and line 61 into mixer 53. In this illustration, 12 moles of liquid HF are used per mole of polyethylbenzene present in mixer 53. BF₃ from source 18 is passed by way of valved line 62 and line 63 into mixer 53. In this illustration, 0.4 mole of BF₃ are used per mole of polyethylbenzene present in mixer 53.

Mixer 53 is provided with heat exchanger 64. Mixer 53 may be similar in construction to mixer 13. The temperature of the materials in mixer 53 is adjusted to 140° F. The materials are passed from mixer 53 by way of line 66 into reactor 67. Reactor 67 is a vessel provided with heat exchangers 68 and 69. These heat exchangers serve to maintain the temperature of contacting at about 140° F. for a total contacting time of about 45 minutes. Reactor 67 is also provided with a turbomixer 71 which is driven by motor 72. In order to improve the degree of conversion of diethylbenzene, the contents of reactor 67 are thoroughly agitated by means of turbomixer 71. Two liquid phases are present in reactor 67, namely, a benzene-ethylbenzene phase and a liquid HF solution phase. At the completion of the contacting step, the contents of reactor 67 are passed by way of line 73 into decomposer 74.

Decomposer 74 is provided with an internal heater 76. Decomposer 74 is similar in construction to decomposer 31 and may be operated in a similar fashion. In this illustration, decomposer 74 is operated at a bottoms temperature of about 70° F. under a slight vacuum. The HF vapors and BF₃ pass overhead through line 77, vacuum pump 78 and line 79 into heat exchanger 81. The HF is condensed in heat exchanger 81 and the mixture of liquid HF and gaseous BF₃ is passed by way of line 82 into separator 83.

Separator 83 is similar in construction to separator 39. The gaseous BF₃ from separator 83 is cycled by way of line 63 to mixer 53. The liquid HF, saturated with BF₃, from separator 83 is cycled by way of line 61 to mixer 53.

The hydrocarbon bottoms from decomposer 74 is passed through line 86 into fractionator 87 which is provided with internal heat exchanger 88. From fractionator 87, a benzene fraction is taken overhead through valved line 89. This benzene fraction is cycled by way of valved line 89 and lines 54 and 56 to mixer 53.

The benzene-free hydrocarbons are removed from the bottom of fractionator 87 and are passed through line 91

into fractionator 92, which is provided with internal heat exchanger 93. From fractionator 92, a substantially pure product ethylbenzene is taken overhead by way of line 94 and is sent to storage not shown.

The bottoms fraction in fractionator 92 consists of diethylbenzene, triethylbenzene and some higher boiling alkylbenzenes. This bottoms fraction is withdrawn from fractionator 92 through valved line 96 and is cycled by way of line 52 to mixer 53. In order to reduce the amount of higher boiling alkylbenzenes in the recycle stream, periodically the bottoms from fractionator 92 are withdrawn and a narrow cut diethylbenzene fraction and a narrow cut triethylbenzene fraction obtained by fractional distillation; these narrow cut fractions are then charged to mixer 53.

In order to show some of the results obtainable by the ethylbenzene conversion process and the diethylbenzene conversion process, the following experimental runs are described.

These runs were carried out using a carbon steel reactor provided with a 1725 R. P. M. stirrer. In all runs, the order of addition was: (1) feed, (2) liquid HF and (3) BF_3 . The contents of the reactor were brought to the desired temperature and were agitated for the desired contacting time. At the completion of the contacting time, the stirring was stopped and the contents permitted to settle for about 10 minutes. The contents of the reactor were withdrawn in such a manner that two liquid phases (if any existed therein) were withdrawn into separate receivers. The liquid phase(s) was withdrawn into a copper vessel filled with crushed ice. Decomposition of the complexes by the water resulted in the formation of a lower aqueous layer and an upper hydrocarbon layer. The hydrocarbon layer was washed with dilute aqueous caustic to remove HF and BF_3 remaining therein and was then water washed to remove traces of the aqueous caustic.

The product hydrocarbons were fractionated in a laboratory column providing about 30 theoretical plates. The narrow cuts were analyzed by a combination of specific gravity, boiling point, refractive index, ultraviolet and infrared techniques.

Runs A through D, shown in Table I, were made to note the effect of varying BF_3 usage, contacting time, temperature and the presence of a raffinate phase, while holding other conditions constant.

TABLE I

Run No.	A	B	C	D
Temperature, °F.	75	70	75	145
Contacting Time, Minutes	30	30	30	30
Reactor Charge, Moles:				
m-xylene	1.60	1.60	0.82	2.41
p-xylene	1.60	1.60	0.81	
Ethylbenzene	1.60	1.60	0.81	0.83
n-heptane (Vol. percent on feed)	None	None	(50%)	None
HF	30.0	60.0	30.0	22.5
BF_3	2.0	5.1	2.7	3.34
Molar Ratios:				
HF/Aromatic	6.2	12.5	12.3	7.0
BF_3 /Xylenes	0.68	1.59	1.66	1.39
BF_3 /Aromatics	0.42	1.06	1.11	1.03
Product Distribution, Mole Percent				
Benzene	8.3	16.7	0.12	0.10

Run A shows that the use of less than 1 mole of BF_3 per mole of xylene in the feed at otherwise constant conditions results in a C₁₀ aromatic hydrocarbon product

containing both diethylbenzene and ethylxylene. (Within the limit of experimental error, the product diethylbenzene consisted of the meta-isomer and the product ethylxylene consisted of the 1,3-dimethyl-5-ethylbenzene.)

Furthermore, Run B shows that by the use of about 1 mole of BF_3 per mole of aromatic hydrocarbon in the feed that the degree of conversion of the ethylbenzene is substantially triple that of Run A.

Run D shows the effect of operating at a temperature above about 125° F. Run D had a contacting time of 30 minutes in order to maximize the ethylxylene production. However, at this high temperature any practicable contacting time, i. e., more than a few seconds, would result in a C₁₀ aromatic hydrocarbon product containing both diethylbenzene and ethylxylene.

Run C shows the effect of a separate phase of non-aromatic hydrocarbons on (1) the degree of conversion of the ethylbenzene, (2) the overall yield of C₈ aromatic hydrocarbons and (3) the presence of side reactions leading to high boiling aromatic hydrocarbon production.

Thus under conditions involving a feed containing 50 volume percent of n-heptane and 50% of C₈ aromatic hydrocarbons and an excess of BF_3 over that theoretically needed to complex the aromatic hydrocarbons, fully one-third of the aromatic hydrocarbons passed into the raffinate phase. Thus in a commercial operation involving a close boiling mixture of C₈ aromatic hydrocarbons and non-aromatic hydrocarbons, these aromatic hydrocarbons could be recovered only by special treatment of the non-aromatic hydrocarbon-rich raffinate.

Further, Run C shows that about one-half of the ethylbenzene in the feed passed into the raffinate phase and was not converted to the desired diethylbenzene. Also, it is of interest that about one-half of the benzene produced in the disproportionation reaction was found in the raffinate phase. Although the overall ethylbenzene conversion was 50%, it is noteworthy that the C₁₀ aromatic hydrocarbons in the extract phase correspond to an 85% conversion of the ethylbenzene remaining in the liquid HF extract phase.

In order to determine the solubility of non-aromatic hydrocarbons in complex-containing liquid HF, two runs were made. In these runs, the aromatic hydrocarbon was mesitylene because this hydrocarbon forms a very stable complex with HF and BF_3 . The non-aromatic hydrocarbon in these runs was n-heptane.

Runs E and F

In these runs, an agitated pressure vessel was used as the interaction zone. The feed was introduced into the

11

vessel followed by the liquid HF and the BF_3 . Commercial grade anhydrous hydrofluoric acid was used as the liquid HF and commercial grade boron trifluoride was the source of the BF_3 . The reactor and its contents were cooled to the desired temperature and the agitation continued for the desired length of time. In the runs herein, only one liquid phase was present in the reactor. At the end of the contacting time, the contents of the reactor were withdrawn into a vessel containing cold water in order to decompose the complex. The water temperature in the quenching vessel was maintained at below about 80° F. The oil layer was decanted from the aqueous layer and was immediately washed with aqueous caustic solution, water washed to remove caustic and dried to remove water. The yield of oil in each of the runs was about 85 volume percent of the feed charged to the reactor. The oil loss is believed to consist mainly of product benzene with some loss of the C_8 aromatic hydrocarbon also.

The mixture of hydrocarbons recovered from the reactor was carefully distilled in a super-fractionation column and the composition of the total product determined by inspection of the distillation curves.

In run No. E, the feed consisted of 3 parts by volume of C. P. orthoxylene and 25 parts by volume of C. P. ethylbenzene. In Run F, the feed was a concentrate of C_8 aromatic hydrocarbons, derived by extractive distillation with phenol from the hydroformate produced in catalytic reforming over molybdena in the presence of hydrogen, of a virgin petroleum naphtha. This fraction contained about 3 volume percent non-aromatic hydrocarbons and had a sulfur content of about 0.01 weight percent. In addition to the C_8 aromatic hydrocarbons, a slight amount of C_9 aromatic hydrocarbons were present. The distribution of C_8 aromatic hydrocarbons in mole percent was: Ethylbenzene, 12; ortho-xylene, 21; meta-xylene, 48; and para-xylene, 19.

The operating conditions and product distribution are set out in Table II following:

TABLE II

Run No.	E	F
Feed	Ethyl benzene o-xylene	C_8 Mix- ture
HF, moles/mole of feed	11.2	11.2
BF_3 , moles/mole of feed	1.9	1.0
Temperature, ° F	66	66
Time, Minutes	10	5
Recovered Product Distribution:		
Benzene	9	5
Ethylbenzene	2	7
Xylenes	59	63
C_9 Aromatics		8
Diethylbenzene ¹	5	2
1,2-dimethyl-4-ethylbenzene ²	21	11
Heavier	4	4
		55

¹ Pure meta-isomer by infra-red.

² 185°-190° C. fraction (98+ % 1,2,4-isomer by infra-red).

No attempt was made to adjust the product distribution obtained by distillation from the recovered liquid product for the loss of benzene and C_8 aromatic hydrocarbons in the water decomplexing operation. Therefore, the product distributions are of value as showing the purity of the diethylbenzene and ethylxylene produced. In view of the results of the earlier runs and the limitations of the infrared procedure, it is believed that the 185°-190° C. product fraction produced in Runs E and F consists only of 1,2-dimethyl-4-ethylbenzene.

Runs E and F show that ortho-xylene does not behave like meta-xylene and para-xylene. In these runs, at 66° F. and times of only 5 and 10 minutes, ortho-xylene and ethylbenzene interacted, whereas in Run B, which was at 70° and a time of 30 minutes, i. e., six times as long as Run F, no interaction of meta-xylene or para-xylene and ethylbenzene took place.

12

Run G

In this run, 170 ml. (1.22 moles) of mesitylene and 25 ml. of n-heptane were contacted with 25 moles of liquid HF and 1.03 moles of BF_3 for 45 minutes at 70° F. The contents of the reactor were settled for 60 minutes and then withdrawn. Two phases were present in the reactor.

The hydrocarbons recovered from the raffinate phase consisted of 21.3 ml. of n-heptane and 13.5 ml. of mesitylene. The hydrocarbons from the extract phase consisted of 3.7 ml. of n-heptane and 156.5 ml. of mesitylene (1.13 moles). Thus the extract hydrocarbons contained 2.4 volume percent of non-aromatic hydrocarbon. It is of interest that there was present in the extract phase 0.1 mole of mesitylene more than the theoretical amount of 1.03 moles. (It has been found that 1 mole of mesitylene and 1 mole of BF_3 are present in a mesitylene- BF_3 -HF complex.)

Run H

This run was carried out to see if a feed corresponding to the extract hydrocarbons of Run E could be treated to form a single liquid phase. Thus 171 ml. (1.23 moles) of mesitylene and 3.7 ml. of n-heptane were contacted with 25 moles of liquid HF and 1.03 moles of BF_3 under the same conditions as described in Run G. When the contents of the reactor were withdrawn only a single phase was found to be present therein. Thus it was possible to form a single liquid phase by treating a feed consisting of 2.1 volume percent of non-aromatic hydrocarbon and the remainder polyalkyl aromatic hydrocarbon by the use of only 0.85 mole of BF_3 per mole of aromatic hydrocarbon in the feed. The solubility of mesitylene in liquid HF alone is about 3 volume percent. Thus about 15 ml. of mesitylene could be dissolved in addition to the amount complexed. Thus about 16 ml. of mesitylene were brought into solution through the solubilizing action of the complex. Heptane is substantially insoluble in liquid HF alone so that virtually the entire amount dissolved in the complex containing liquid HF is due to the solubilizing action of the complex.

Run I

This run illustrates the results obtainable with the diethylbenzene conversion process. Benzene, 1,3-diethylbenzene, liquid HF and BF_3 were contacted for 16 hours at a temperature of 61° F. The pertinent information on this run is given below:

Temperature, ° F	61
Time, hours	16
Reactor charge—moles:	
Benzene	3.03
1,3-diethylbenzene	1.03
HF	13.8
BF_3	0.45

Molar ratios:

HF/diethylbenzene	13.4
BF_3 /diethylbenzene	0.44

Product distribution:	Moles
Benzene	2.40
Ethylbenzene	1.32
Diethylbenzene	.22
Triethylbenzene	.12

Yield of ethylbenzene (Percent of theo.)	64

The product from this run contained no detectable amounts of compounds other than those listed. Within experimental error, the triethylbenzene consisted of the 1,3,5-isomer.

This is a continuation-in-part of our copending application Serial No. 312,278, filed September 30, 1952, now abandoned.

Thus having described our invention, what is claimed is:

1. A process for the treatment of a mixed feed consisting essentially of at least one xylene selected from the class consisting of meta-xylene and para-xylene and ethylbenzene for the production of diethylbenzene and a xylene product that is substantially free of ethylbenzene, which process comprises contacting said feed with at least about 1 mole of BF_3 per mole of aromatic hydrocarbons in said feed and with between about 2 and 50 moles of liquid HF per mole of aromatic hydrocarbons in said feed, at a temperature between about 0° and 125° F. for a time between that which is sufficient to substantially attain an equilibrium condition in the disproportionation of said ethylbenzene to diethylbenzene and benzene and not more than between about 2 minutes and 50 hours, the longer maximum times corresponding to the lower temperature, removing HF and BF_3 from said liquid HF-phase to recover hydrocarbons therefrom and separating a xylene fraction that is substantially free of ethylbenzene and a diethylbenzene fraction from said hydrocarbons.

2. The process of claim 1 wherein said BF_3 is present in an amount of about 1.5 moles per mole of said aromatic hydrocarbon, said liquid HF is present in an amount between about 6 and 15 moles per mole of said aromatic hydrocarbon and the contacting is maintained at a temperature between about 70° and 100° F. for a time between that necessary to substantially attain said equilibrium condition and not more than between about 10 minutes and 30 minutes, the longer maximum times corresponding to the lower temperature.

3. A process for the production, without appreciable loss of xylene, of a xylene fraction that is substantially free of ethylbenzene, which process comprises contacting a close boiling feed consisting essentially of a mixture of C_8 aromatic hydrocarbons and not more than about 3% of non-aromatic hydrocarbons, which has been fractionated to remove essentially all the o-xylene, with between about 6 and 15 moles of liquid HF per mole of aromatic hydrocarbon in said feed and between about 1.5 and 3 moles of BF_3 per mole of aromatic hydrocarbon in said feed, at a temperature between about 0° and 125° F. for a time between about 2 minutes and 50 hours, the longer time corresponding to the lower temperature, separating a raffinate phase comprising essentially non-aromatic hydrocarbons and ethylbenzene from an extract phase, recovering an extract by removing HF and BF_3 from said

extract phase, and separating by fractional distillation a xylene fraction, that is substantially free of ethylbenzene, from said extract.

4. A process for the preparation of xylene that is substantially free of ethylbenzene and of substantially pure ethylbenzene from a mixed feed consisting essentially of at least one xylene isomer other than o-xylene and of ethylbenzene, which process comprises the steps of (1) contacting said feed with between about 1.5 and 3 moles of BF_3 per mole of aromatic hydrocarbon in said feed and between about 6 and 15 moles of liquid HF per mole of aromatic hydrocarbon in said feed, at a temperature between about 70° and 100° F. for a time sufficient to attain substantially the equilibrium condition in the formation of diethylbenzene, (2) separating hydrocarbons from HF and BF_3 , (3) separating by distillation said hydrocarbons into (a) a benzene fraction, (b) a xylene fraction that is substantially free of ethylbenzene and (c) a diethylbenzene fraction, (4) passing the diethylbenzene and the benzene of step (3) to a second contacting zone, (5) introducing to said second zone additional benzene, (6) intimately contacting the hydrocarbons present in said second zone with between about 10 and 25 moles of liquid HF per mole of polyethylbenzene in said second zone and between 0.3 and 0.5 mole of BF_3 per mole of polyethylbenzene in said second zone, at a temperature between about 100° and 150° F. for a time between about 30 minutes and 2 hours, the longer times corresponding to the lower temperatures, and wherein the benzene from step (3) and the additional benzene of step (5) amount to between about 4 and 7 moles per mole of transferable ethyl group present in said second zone, (6) separating mixed hydrocarbons from HF and BF_3 , (7) separating by distillation said mixed hydrocarbons into (a) a benzene fraction, (b) a substantially pure ethylbenzene fraction and a polyethylbenzene fraction, and (8) cycling the benzene and polyethylbenzene fractions of step (7) to said second contacting zone.
